UNITED STATES PATENT OFFICE.

EDWARD G. THOMAS, OF BOSTON, MASSACHUSETTS.

DESIGN FOR A FILM-HOLDER.

SPECIFICATION forming part of Design No. 29,112, dated July 26, 1898.

Application filed April 25, 1898. Serial No. 678,805. Term of patent 7 years.

To all whom it may concern:

Be it known that I, EDWARD G. THOMAS, of Boston, in the county of Suffolk and State of Massachusetts, have invented and produced 5 a new and original Design for Film-Holders, of which the following is a specification, reference being had to the accompanying drawing, forming a part thereof.

In the drawing a perspective of the film- 10 holder is shown.

The leading or material feature of the design consists in the unitary article made the subject of the illustration—that is to say, in the film-holder having the shape and configuration shown and described specifically it has 15 the end bars A A', the side bars B B', the

overlapping extensions C C' of the side bars, which are separated from the side bar by the longitudinal recesses c c', the cross-bar d, and the handle or finger d', the design forming a 20 frame surrounding the openings D, which are substantially rectangular in shape.

Having described my invention, what I claim as new, and desire to secure by Letters Patent of the United States, is—

The design for a film-holder as herein 25 shown and described.

EDWARD G. THOMAS.
